UNITED STATES PATENT OFFICE.

LOUIS DI CARLO, OF CLEVELAND, OHIO.

KNOCKDOWN BOAT.

1,333,248.

Specification of Letters Patent. Patented Mar. 9, 1920.

Application filed August 9, 1918. Serial No. 248,195.

To all whom it may concern:

Be it known that I, LOUIS DI CARLO, a subject of the King of Italy, residing at Cleveland, in the county of Cuyahoga and State of Ohio, have invented certain new and useful Improvements in Knockdown Boats, of which the following is a specification.

This invention relates to a boat for army use and has for its object to provide a very light collapsible boat which may be carried by soldiers or others upon their backs and easily set up at a river it is desired to cross quickly.

Another object of the invention is to provide a collapsible boat having an independent, knock down frame structure.

A still further object of the invention is to provide a boat having a double canvas body provided with reinforcing plates between the layers of canvas.

With the above and such other objects in view as will hereinafter more fully appear, I have invented the boat illustrated in the accompanying drawings in which—

Figure 1 is an elevational view of my boat.

Fig. 2 is a top plan view thereof.

Fig. 3 is a transverse sectional view.

Fig. 4 is a plan view of the canvas pattern from which the body of the boat is formed.

Fig. 5 is a perspective view of the bottom of the shell after having been formed.

Fig. 6 is a perspective view of the shell shown collapsed.

Fig. 7 is a perspective view of the same shown folded and having the frame members folded and placed therein.

Fig. 8 shows the entire device formed into a pack, inclosed in a knapsack and strapped to the shoulders of a person.

Fig. 9 is a detail view of a frame member shown folded.

Fig. 10 is a keel rib shown folded.

Fig. 11 is a plan view of a rib joint.

Like reference characters indicate like parts throughout the following specification and in the several views in the drawings in which 1 indicates a collapsible boat the shell of which is formed from a single piece of canvas 2 the portions 3 and 4 of which have cut-outs 5, 6, 7, and 8 and which is doubled upon itself to form inner and outer walls 9 and 10. Between these walls are secured spaced apart reinforcing and stiffening

plates 11 and 12, the plates 11 being in the side walls of the boat and the plates 12 in the bottom 13 thereof. The plates 11 are preferably rectangular in shape and of a size to suit the particular size of the boat 60 desired. These plates are so spaced apart that the shell may fold accordion fashion one layer upon the other at 15 and 19, after which the various separable and foldable frame members are placed between the various layers 17 and 18 and stacked upon the upper layer of the folded shell and the pack placed in the knapsack 20 having straps 21 and 22 whereby the same may be secured to the back of a person as shown in Fig. 8 70 of the drawings.

The bottom plates 12^a and 12^b are cut tapering to conform to the tapering ends 21' and 22' of the boat and the longitudinal rows of plates 12^c and 12^d are spaced apart 75 at the longitudinal central line 23 in order that the shell may be folded upon itself at that line. These plates are also spaced apart transversely at the hinge lines 15 and 19 so as to permit folding of the shell on those 80 lines. They are also spaced apart at intermediate points, as are plates 11 to permit compact folding of the shell.

The upper edges of side walls 24 and 25 are provided with a series of spaced apart 85 supporting plates 26, each being provided with bayonet joint slots 27 to receive the bolts 28', in the edge of frame 28, upon which thumb nuts 29 are provided to hold the members securely bolted together. The frame 28 consists of bow and stern plates 29'' and 30 and side members 31, 32, 33, and 34, each of which is formed of a pair of sections connected by hinges whereby they may be folded upon one another; these members are also 90 provided with hooks or other suitable device at the hinged joint whereby they may be held rigidly opened when the boat is set up. The members 31 and 32 and the members 33 and 34 are when set up secured together by plates 39 and 40 connected by thumb bolts 41 and these joints are held rigid by hooks 43, or any other suitable means. The frame members 31, 32, 33, and 34 are secured to the end members 29'' and 30 by bolted together plates 44 and 45 and hooks 46.

A series of U-shaped rib members 47 are suitably spaced apart throughout the length of the boat, each of these members consists of a transverse bottom brace 48 having up- 110

right ribs 49 and 50 hinged to its ends at 51 and 52. The upper ends of the ribs seat directly under the members 31 to 34 and are secured thereto by hooks 53 engaging the eyes 54 in said members 31—34. A keel rib 55 extends longitudinally of the center of the bottom 13 and seats under the centers of the members 48, which are provided with recesses 56 to interlock with the recesses 57 formed at the joints 58 of said keel rib. This rib is formed of a series of sections 59 connected by flat hinge plates 60 and 61, connected by bolts 62 and 63 and are so arranged that the keel rib may fold upon itself edge-wise into a compact space as indicated in Fig. 11. The bow end of the keel rib is provided with an elongated brace rod 64 hinged thereto and having an elongated eye 65 in its upper end to engage the screw eye 66 in the 20 edge of bow plate 29".

From the above description it will readily be seen that I have provided a very light yet very substantial knock-down boat which may be folded in its entirety into a compact 25 bundle and placed in a knapsack to be carried by anyone. The boat which I have constructed for demonstration purposes will easily carry one or two men and weighs only 32 pounds and I can pack the same for several miles without fatigue. While this boat is especially adapted for use of armies whereby large numbers of men may cross rivers without much interference, it is at the same time excellently adapted for use where- 30 ever a knock-down or folding boat is desired, such for instance, as camping, fishing and hunting trips and for general use. It is also well adapted for use as a sporting boat for use in surf and river bathing as its 35 lightness makes it easy to handle and right when it upsets by heavy waves.

A special advantage of having the canvas doubled is that if either wall becomes punctured the other wall will prevent leakage 40 into the boat. The plates 11 and 12 are held in place by bolts 67 or in any other suitable manner. Skid members 68 suitably spaced apart are provided on the bottom of the boat. These members are held in place by 45 bolts 69 which extend through the canvas as well as through the plates 12. The canvas shell of the boat is formed by cutting the pattern as indicated in Fig. 4 the edges 70, 71, 72 and 73 being sewed together to form 50 the seam 74 and the edges 75, 76, 77 and 78 being sewed together to form the seam 79 the stitching being done after the parts 3 and 4 are doubled upon one another and the plates 11 and 12 secured in place. On the 55 horizontal portion 48 of one of the centrally disposed U-shaped members 47 are a pair of hinged hooks 80 and 81 adapted to engage eyes 82 and 83 in the upright arms 49 and 50 thereof and form braces to help hold 60 the side walls of the boat out at their cen-

tral portion. Openings 87 are provided in the transverse members of the U-ribs 47 to receive the points 86 of the hooks 53.

Having now described my invention, that which I claim to be new and desire to procure by Letters Patent is:—

1. In a boat a shell formed of a plurality of layers of fabric, and a series of plates interposed between said layers extending throughout the entire bottom and sides 75 thereof.

2. In a boat a shell, the bottom and sides of said shell being formed of a plurality of layers of fabric, a series of plates interposed between said layers and extending throughout both the sides and bottom thereof, said plates all being spaced apart. 80

3. In a boat a shell, the sides and bottom of said shell being formed of a plurality of layers of fabric, a series of plates interposed between said layers extending throughout both the sides and bottom thereof, said plates all being spaced apart, certain of said spaced parts forming hinged portions whereby the shell may be folded. 85

4. In a boat a shell, the sides and bottom of said shell being formed of a plurality of layers of fabric, a series of plates interposed between said layers extending throughout both the sides and bottom thereof, said plates all being spaced apart, certain of said spaced parts forming hinged portions whereby the shell may be folded, longitudinally. 95

5. In a boat a shell, the sides and bottom of said shell being formed of a plurality of layers of fabric, a series of plates interposed between said layers extending throughout both the sides and bottom thereof, said plates all being spaced apart, certain of said spaced parts forming hinged portions whereby the shell may be folded, longitudinally, and transversely. 100

6. In a boat a shell, the sides and bottom of said shell being formed of a plurality of layers of fabric, a series of plates interposed between said layers extending throughout both the sides and bottom thereof, said plates all being spaced apart, certain of said spaced parts forming hinged portions whereby the shell may be folded, longitudinally, and transversely, an upper foldable frame for said boat. 115

7. In a boat a shell, the sides and bottom of said shell being formed of a plurality of layers of fabric, a series of plates interposed between said layers extending throughout both the sides and bottom thereof, said plates all being spaced apart, certain of said spaced parts forming hinged portions whereby the shell may be folded, longitudinally, and transversely, an upper foldable frame for said boat, lock plates on the upper edges of the shell for engagement with the frame. 125

8. In a boat a shell, the sides and bottom 130

of said shell being formed of a plurality of layers of fabric, a series of plates interposed between said layers extending throughout the bottom and sides thereof, said plates all being spaced apart, certain of said spaced parts forming hinged portions whereby the shell may be folded, longitudinally, and transversely, an upper foldable frame for said boat, lock plates on the upper edges of the shell for engagement with the frame, said frame being formed in a plurality of independent sections.

9. In a boat a shell formed of a plurality of layers of fabric, plates interposed between said layers, said plates all being spaced apart, certain of said spaced parts forming hinged portions whereby the shell may be folded, longitudinally, and transversely, an upper frame for said boat, lock plates on the upper edges of the shell for engagement with the frame, said frame being formed in a plurality of independent sections, certain of said sections being formed in hingedly connected sections.

25 10. In a boat a shell formed of a plurality of layers of fabric, plates interposed between said layers, said plates all being spaced apart, certain of said spaced parts forming hinged portions whereby the shell may be folded, longitudinally, and transversely, an upper frame for said boat, lock plates on the upper edges of the shell for engagement with the frame, said frame being formed in a plurality of independent sections, certain 30 of said sections being formed in hingedly connected sections, means for supporting all of said sections horizontally.

11. In a boat a shell formed of a plurality of layers of fabric, plates interposed between 40 said layers, said plates all being spaced apart, certain of said spaced parts forming hinged portions whereby the shell may be folded, longitudinally, and transversely, an upper frame for said boat, lock plates on the upper edges of the shell for engagement with the frame, said frame being formed in a plurality of independent sections, certain of said sections being formed in hingedly connected sections, means for supporting 45 all of said sections horizontally, said means embracing U-shaped ribs.

12. In a boat a shell formed of a plurality of layers of fabric, plates interposed between 55 said layers, said plates all being spaced apart, certain of said spaced parts forming hinged portions whereby the shell may be folded, longitudinally, and transversely, an upper frame for said boat, lock plates on the upper edges of the shell for engagement with the frame, said frame being formed in a plurality of independent sections, certain of said sections being formed in hingedly connected sections, means for supporting 60 all of said sections horizontally, said means embracing U-shaped ribs, said

ribs being formed in hingedly connected sections.

13. In a boat a shell formed of a plurality of layers of fabric, plates interposed between said layers, said plates all being spaced apart, certain of said spaced parts forming hinged portions whereby the shell may be folded, longitudinally, and transversely, an upper frame for said boat, lock plates on the upper edges of the shell for engagement 75 with the frame, said frame being formed in a plurality of independent sections, certain of said sections being formed in hingedly connected sections, means for supporting all of said sections horizontally, said means 80 embracing U-shaped ribs, said ribs being formed in hingedly connected sections, a keel rib adapted to be mounted under said U-shaped ribs.

14. In a boat a shell formed of a plurality of layers of fabric, plates interposed between said layers, said plates all being spaced apart, certain of said spaced parts forming hinged portions whereby the shell may be folded, longitudinally, and transversely, an upper frame for said boat, lock plates on the upper edges of the shell for engagement with the frame, said frame being formed in a plurality of independent sections, certain of said sections being 90 formed in hingedly connected sections, means for supporting all of said sections horizontally, said means embracing U-shaped ribs, said ribs being formed in hingedly connected sections, a keel rib adapted to be mounted under said U-shaped ribs, 100 and held in place thereby.

15. In a boat a shell formed of a plurality of layers of fabric, plates interposed between said layers, said plates all being 105 spaced apart, certain of said spaced parts forming hinged portions whereby the shell may be folded, longitudinally, and transversely, an upper frame for said boat, lock plates on the upper edges of the shell for engagement with the frame, said frame being formed in a plurality of independent sections, certain of said sections being formed in hingedly connected sections, means for supporting all of said sections 110 horizontally, said means embracing U-shaped ribs, said ribs being formed in hingedly connected sections, a keel rib adapted to be mounted under said U-shaped ribs and held in place thereby, said keel rib being formed 120 in a plurality of hingedly connected sections.

16. In a boat a shell formed of a plurality of layers of fabric, plates interposed between said layers, said plates all being 125 spaced apart, certain of said spaced parts forming hinged portions whereby the shell may be folded, longitudinally, and transversely, an upper frame for said boat, lock plates on the upper edges of the shell for 130

- engagement with the frame, said frame being formed in a plurality of independent sections, certain of said sections being formed in hingedly connected sections, 5 means for supporting all of said sections horizontally, said means embracing U-shaped ribs, said ribs being formed in hingedly connected sections, a keel rib adapted to be mounted under said U-shaped 10 ribs, and held in place thereby, said keel rib being formed in a plurality of hingedly connected sections, whereby the same may be folded.
17. In a boat a shell formed of a plurality of layers of fabric, plates interposed between said layers, said plates all being spaced apart, certain of said spaced parts forming hinged portions whereby the shell may be folded, longitudinally, and transversely, an upper frame for said boat, lock plates on the upper edges of the shell for engagement with the frame, said frame being formed in a plurality of independent sections, certain of said sections being 25 formed in hingedly connected sections, means for supporting all of said sections horizontally, said means embracing U-shaped ribs, said ribs being formed in hingedly connected sections, a keel rib adapted to be mounted under said U-shaped 30 ribs, said keel rib having a plurality of recesses adapted to be engaged by similar recesses in said U-shaped ribs.
18. In a boat a shell formed of a plurality of layers of fabric, plates interposed between said layers, said plates all being spaced apart, certain of said spaced parts forming hinged portions whereby the shell may be folded, longitudinally, and transversely, an upper frame for said boat, lock plates on the upper edges of the shell for engagement with the frame, said frame being formed in a plurality of independent sections, certain of said sections being 45 formed in hingedly connected sections, means for supporting all of said sections horizontally, said means embracing U-shaped ribs, said ribs being formed in hingedly connected sections, a keel rib adapted to be mounted under said U-shaped 50 ribs and held in place thereby, said keel rib being formed in a plurality of hingedly connected sections, whereby the same may be folded, said keel rib having a plurality of recesses adapted to be engaged by similar recesses in said U-shaped ribs, whereby the 55 keel and U-ribs are secured together.
19. In a boat a shell formed of a plurality of layers of fabric, plates interposed between said layers, said plates all being spaced apart, certain of said spaced parts forming hinged portions whereby the shell may be folded, longitudinally, and transversely, an upper frame for said boat, lock plates on the upper edges of the shell for 60 engagement with the frame, said frame being formed in a plurality of independent sections, certain of said sections being formed in hingedly connected sections, means for supporting all of said sections horizontally, said means embracing U-shaped ribs, said ribs being formed in hingedly connected sections, a keel rib adapted to be mounted under said U-shaped 65 ribs, said keel rib having a plurality of recesses adapted to be engaged by similar recesses in said U-shaped ribs, whereby the keel and U-ribs are secured together.
20. In a boat a shell formed of a plurality of layers of fabric, plates interposed between said layers, said plates all being spaced apart, certain of said spaced parts forming hinged portions whereby the shell may be folded, longitudinally, and transversely, an upper frame for said boat, lock plates on the upper edges of the shell for engagement with the frame, said frame being formed in a plurality of independent 70 sections, certain of said sections being formed in hingedly connected sections, means for supporting all of said sections horizontally, said means embracing U-shaped ribs, said ribs being formed in hingedly connected sections, a keel rib adapted to be mounted under said U-shaped 75 ribs, said keel rib having a plurality of recesses adapted to be engaged by similar recesses in said U-shaped ribs, whereby the keel and U-ribs are secured together, said U-ribs being adapted to hold the sections of the keel rib rigidly together. 80
21. In a collapsible boat, a plurality of U-shaped ribs each comprised of a plurality of jointed sections, and an upper edge foldable frame to which certain of said ribs are secured, said frame being formed of a series of detachably connected sections. 85
22. In a collapsible boat, a plurality of U-shaped ribs each comprised of a plurality of jointed sections, an upper edge foldable frame to which certain of said ribs are secured, said frame being formed of a series of detachably connected sections, and a jointed keel held in place by said U-ribs. 90
23. In a collapsible boat, a boat shell, a plurality of U-shaped ribs each comprised of a plurality of jointed sections, an upper edge foldable frame to which certain of said ribs are secured, said frame being formed of a series of detachably connected sections, a jointed keel rib held in place by 95 said U-ribs, and means for securing said frame to the boat shell. 100
24. In a collapsible boat a plurality of independent U-shaped detachable ribs, the arms of said ribs being foldable upon one 105

another, a keel rib forward of a series of foldable hingedly connected sections and interlocked with each U-shaped rib at the recessed end portion of each of said sections.

5 25. In a collapsible boat a plurality of independent U-shaped detachable ribs, each provided with a recessed central portion, the arms of said ribs being foldable upon one another, a keel rib held in place by said U-ribs, said keel rib being formed of a series of hingedly connected sections and interlocked with each U-shaped rib and the recessed end of each section. 55

10 26. In a collapsible boat a plurality of independent U-shaped detachable ribs, each rib having a recessed central portion, the arms of said ribs being foldable upon one another, a keel rib held in place by said U-ribs, said keel rib being formed of a series 60

20 of foldable hingedly connected sections, all of said ribs being interlocked together at the recessed end portion of each of said sections. 65

25 27. In a collapsible boat a plurality of independent U-shaped detachable ribs, the arms of said ribs being foldable upon one another, a keel rib held in place by said U-ribs, said keel rib being formed of a series of 70

30 foldable hingedly connected sections, all of said ribs being interlocked together at the recessed end portion of each of said sections, a rigid upper edge frame for said boat. 75

35 28. In a collapsible boat, a plurality of independent U-shaped detachable ribs, the arms of said ribs being foldable upon one another, a keel rib held in place by said U-ribs, said keel rib being formed of a series 80

40 of foldable hingedly connected sections, all of said ribs being interlocked together at the recessed end portion of each of said sections, a rigid foldable upper edge frame for said boat, to which certain of said ribs 85

45 are secured.

29. In a collapsible boat a plurality of independent U-shaped detachable ribs, the arms of said ribs being foldable upon one another, a keel rib held in place by said U-ribs, said keel rib being formed of a series 90

50 of hingedly connected sections, all of said ribs being interlocked, a rigid upper edge frame for said boat, to which certain 95

means whereby all of said ribs and sections are rigidly connected, and means for securing said frame to the boat shell.

In testimony whereof I affix my signature in the presence of two witnesses.

LOUIS DI CARLO.
